FIG. 6.

By his Attorney *Maurice B. Block* Inventor
Elles E. Hartman

UNITED STATES PATENT OFFICE.

ELLÉS E. HARTMAN, OF NEW YORK, N. Y., ASSIGNOR OF ONE-THIRD TO ETHEL E. HARTMAN, OF NEW YORK, N. Y., AND ONE-THIRD TO ARTHUR P. CAMPBELL, OF WICHITA, KANSAS.

AIRPLANE.

1,371,240.

Specification of Letters Patent. Patented Mar. 15, 1921.

Application filed December 24, 1919. Serial No. 347,150.

To all whom it may concern:

Be it known that I, ELLÉS E. HARTMAN, a citizen of Hungary, residing at New York city, county and State of New York, have 5 invented certain new and useful Improvements in Airplanes, of which the following is a full, clear, and exact description.

This invention relates to improvements in airplanes, but chiefly to a safety device to 10 prevent the plane from falling too rapidly either for landing purposes or in case of accident. To carry out my invention, I arrange certain of the wings of the plane, preferably the bottom wings, so that they 15 can be transformed into channel formation, that is to say, transformed into a wing or wings having depending supplemental aprons along the front and rear edges. The object of my invention is to arrange certain 20 of the wings so that air will be pocketed and act as a cushion to prevent an airplane from dropping too rapidly. Under normal conditions, the aprons will be folded against the wing or wings to which they are 25 attached and will not interfere with the function of the wing or wings. In case of accident, due to the stopping of the engine (for instance), the aprons will be released and 30 will drop, thereby adapting the wing or wings to pocket air, whereby considerable 35 resistance will be offered to the dropping plane. The aprons may also be used to effect an easy landing.

I will now proceed to describe the invention 35 in detail, the novel features of which I will finally claim, reference being had to the drawings, wherein:—

Figure 1 is a side elevation of an airplane embodying my improvement;

Fig. 2 is an enlarged cross sectional view 40 of one of the lower planes;

Fig. 3 is an enlarged fragmentary plan view, the upper plane being omitted, and also the canvas of the lower planes;

Figs. 4 and 5 are detail sectional views, 45 taken on lines 4—4 and 5—5 in Fig. 3; and

Fig. 6 is a front end elevation, partly in section, the wings being broken away.

In the accompanying drawings, the fuselage 50 of an airplane is indicated by 7, a top wing by 8 and lower wings by 9. As the remaining elements of an airplane have no bearing upon my invention, they will not be 55 described in detail. As herein arranged, the

bottom wings 9 are made up of the usual wing-member and movable aprons 11 and 12 arranged to lie against the said wing member, as indicated in Fig. 2, or to be lowered as indicated by dotted lines in Fig. 1. 60 In this instance, the aprons 11 and 12 are attached to the rear and front edges, respectively, of the wings 9 by means of hinges 13 and 14, respectively, and are adapted to swing downwardly, as indicated by dotted 65 lines in Fig. 1, to form a channel or pocket, open at both ends, to pocket or receive air. When a plane drops rapidly, it is of course resisted by the air, but air will be forced from under the wings and will flow in a direction parallel with the wings. The aprons 11 and 12 will prevent air from flowing from under the wings excepting gradually. In other words, air will be pocketed in the channel formed by the wing proper and the 70 depending aprons or supplemental wings 11 and 12. The supplemental wings or aprons will be held up against the wings by means of a releasable locking device arranged to be manipulated by the aviator or assistant. To 75 lock the supplemental aprons or wings against the wing proper, I employ an oscillating shaft 15 carried by brackets 16 mounted on the main plane 9. The shaft 15 carries hooks 17 to engage a bar 18 carried by 80 one of the aprons, in this instance apron 12. The apron 12 carries a lip 19^a to overlap the adjacent edge of apron 11; hence apron 11 will be held up by apron 12, owing to the 85 overlapping lip 19^a.

As can be seen in Fig. 3, the shaft 15 extends from the end of one wing 9 to the end of the other wing 9, passing through the fuselage 7. The shaft 15 carries a lever 19 adjacent the seat 20 for the aviator, 90 which, when operated in the proper direction, will rotate shaft 15 and cause the hooks 17 to leave rod 18. To cause the supplemental wings or aprons to drop to the position indicated by dotted lines in 95 Fig. 1, I employ (in this instance) springs 21 connecting arms 22, carried by the aprons 11 and 12, with the upper wing 8. When the rod 18 is released, springs 21 will pull or swing the supplemental aprons or wings 100 11 and 12 downwardly, check cables 23 being employed to prevent said aprons from being moved too far.

To restore the supplemental wings or 105 aprons 11 and 12 to the folded position, 110

- cables 24 and 25 will be employed, which are wound upon drums 26 and 27 adjacent the aviator's seat. The drums 26 and 27 may be rotated by means of a handle 28.
- 5 The cables 24 and 25 will be passed over pulleys 29 carried by the upper wing (see Fig. 6), then downwardly through the main wings 9 and connected to their respective aprons or supplemental wings 11 and 12.
- 10 It will be apparent that the aprons 11 and 12 can be caused to swing downwardly at the will of the aviator and when allowed to assume such position will act to prevent the airplane from falling too rapidly. After
- 15 having been allowed to swing down, the aprons can be raised by means of the rotatable drums 26 and 27.

Having now described my invention, what I claim and desire to secure by Letters Patent is:—

- 20 1. An airplane wing, comprising a main portion, and a supplemental apron or wing of approximately equal area hinged to each longitudinal edge thereof, arranged to be folded against the under surface of the main wing.
- 25 2. An airplane wing, comprising a main portion, a supplemental wing or apron of approximately equal area pivotally connected to each longitudinal edge thereof, and releasable means to normally maintain said aprons in contact with the under surface of the main wing.
- 30 3. An airplane wing, comprising a main

body frame, a supplemental frame pivotally connected to the main frame and adapted to be opened up at will to provide a channel or pocket under said main frame to receive a volume of air, whereby the plane to which the wing is applied will be sustained against a sudden fall, an oscillatory shaft carried by the main frame, hooks carried by the said shaft, a bar carried by the supplemental frame to be engaged by the hooks on the oscillatory shaft, and a lever carried by the oscillatory shaft whereby said shaft can be operated to release the supplemental frame.

- 35 4. In an air plane wing, a main frame, a pair of supplemental frames, each supplemental frame being pivotally connected along the longitudinal edge to the adjacent longitudinal edge of the main frame, a lip carried by one of said supplemental frames, along the inner longitudinal edge 50 to lie under the adjacent edge of the other supplemental frame, a bar carried by the supplemental frame having the lip, releasable latches carried by the main frame to engage said bar, and means to operate the 55 latches.

Signed at New York city, N. Y., this 22 day of December, 1919.

ELLÉS E. HARTMAN.
